OUTDOOR FLUORESCENT LIGHTING FIXTURE, OR SIMILAR ARTICLE

Lawrence E. Roovaart, Arlington Heights, Ill., assignor
to The Pyle-National Company, Chicago, Ill., a corpo-
ration of New Jersey

Filed Nov. 9, 1964, Ser. No. 82,525

Term of patent 14 years

(Cl. D48—20)

FIGURE 1 is a top plan view of an outdoor fluorescent lighting fixture, or similar article, showing my new design; FIGURE 2 is a bottom plan view of the fixture of FIGURE 1;

FIGURE 3 is a side elevational view of the fixture of FIGURE 1;

FIGURE 4 is an end elevational view looking at the end of the fixture at its widest end corresponding to the right end of FIGURE 3;

FIGURE 5 is a profile view of the light diffusion member to better illustrate the shape thereof; and

FIGURE 6 is an end elevational view looking at the end of the fixture at its narrowest end corresponding to the left end of FIGURE 3, but drawn to a different scale to illustrate more clearly the design.

The dominant features of the design reside in those portions appearing in full lines.

I claim:

The ornamental design for an outdoor fluorescent lighting fixture, or similar article, substantially as shown and described.
